CLAIM

(21) Appl. No.: **29/652,677**

I claim the ornamental design for a nozzle attachment for a heat gun for use in heat shrink tube processing, substantially as shown and described.

(22) Filed: **Oct. 23, 2020**

DESCRIPTION

(51) **LOC (13) Cl. 08-05**

FIG. 1 is a front perspective view of the nozzle attachment for a heat gun for use in heat shrink tube processing.

(52) **U.S. Cl.**

FIG. 2 is a top plan view thereof.

USPC **D8/29.1**

FIG. 3 is a bottom plan view thereof.

(58) **Field of Classification Search**

FIG. 4 is a front elevation view thereof.

USPC D8/29.1, 29.2, 30; D15/144, 144.2, 145
CPC A45D 20/08; A45D 20/10; F24H 3/00;
F24H 3/0423

FIG. 5 is a rear elevation view thereof; and,

See application file for complete search history.

FIG. 6 is a left side elevation view thereof, wherein the right side elevation view is a mirror image thereof.

(56) **References Cited**

Structure, environment, and/or boundaries shown in broken lines forms no part of the claimed design.

U.S. PATENT DOCUMENTS

The broken lines in FIG. 3 depict portions of the nozzle attachment for a heat gun for use in heat shrink tube processing in which the design is embodied that form no part of the claimed design.
